UNITED STATES PATENT OFFICE

EMIL FRIEDRICH RUSS, OF COLOGNE, GERMANY

INDUCTION FURNACE

Application filed March 5, 1928, Serial No. 259,272, and in Germany April 20, 1925.

The invention relates to induction furnaces for melting, annealing and similar kinds of industrial heat treatment. The essential feature of the invention is, that a part of the 5 secondary circuit is designed as a heating element.

In the accompanying drawings:

Figure 1 is a vertical transverse sectional view of an induction furnace constructed and 10 arranged in accordance with this invention.

Figure 2 is a similar view of a modified form of the same.

Figure 3 is a vertical sectional view on a plane at right angles to that of Figure 2.

Figure 4 is a vertical sectional view of another modified form of the invention.

Figure 5 is a similar view showing another modified construction of the invention.

Figure 6 is a similar view of another modified form of the invention.

Figure 7 is a sectional view of the same on a plane at right angles to that of Figure 6.

According to the form of the invention shown in Figs. 1-3, the primary winding 2 is 25 fitted at the bottom of the muffle masonry 1 upon an iron yoke. The winding is surrounded by a secondary body 3, open at the top in the shape of a horse-shoe, which is not intended for heating, and is therefore made 30 of large proportions. To the ends of the horse-shoe 3 is connected the heating element 4, by which the secondary circuit is closed.

This heating element 4 consists, according to Fig. 1, of a resistance sheet bent to suitable shape, which lines the muffle walls. Thus, in this case the four interior surfaces of the muffle are connected in series in the secondary circuit. The heating element may consist either of smooth sheets or, in order 40 to lengthen the current path, of sheets alternatively ribbed or corrugated.

A special increase in the length of the current path is obtained by the practical application according to Figs. 2 and 3. The heating element 5 consists of a sheet bent in one length in the manner of a loop to form a double wall, forming three interior surfaces of the muffle. In order that both sides of the double wall may impart their heat uniformly to the interior of the muffle, they are 50

broken by openings 6 displaced the one against the other, as shown in Fig. 3.

In the examples described, almost the entire heat of the secondary circuit is developed in the part designed as a heating element 4, or 55 5 respectively. The stout secondary element 3, on the other hand, only produces a small quantity of heat, owing to its large section. This however is not lost either, but is rendered 60 useful as floor heating for the muffle.

According to the form of the invention shown in Fig. 4 the stout secondary element 7 is so designed as to heat not only the floor, but also the sides of the muffle. For this purpose, it is carried upwards in the masonry, on both sides of the muffle, and connected to the heating element 8 only just below the muffle cover. In the construction illustrated, this element is made of corrugated iron, in order 70 to lengthen the current path.

The small liberation of heat of the stout-walled secondary body may, as well be made use of in a special heat treatment room outside the muffle proper. Thus, according to Fig. 5, for example, there is a preheating 75 chamber 9 below the muffle, within which the stout secondary body 10 is freely suspended. The heating of the muffle may hereby be carried out according to Fig. 1 or any of the other forms of the invention described. 80

If the stout-walled secondary body is not intended to assist in heating, it may be provided with cooling ribs, cooling pins, or the like. With the muffle furnace constructed according to Figs. 6 and 7, for instance, the 85 greater part of the secondary body 11 is situated outside the masonry, and is provided with ribs 12 to increase the cooling surface. The heating element 13 closes the secondary circuit in the manner already described and 90 the interior surface of the muffle.

The stout-walled secondary body may be sub-divided completely in the form of rings, disks, helices, or the like, thereby securing in addition to a large cooling surface, a reduction 95 of eddy current losses.

I claim:

1. In a furnace having a muffle, an electric heating system comprising a primary winding, a secondary winding, and a resistance 100

sheet forming the wall of the muffle chamber, each face of the resistance sheet being in the form of a double wall.

2. A furnace as claimed in claim 1, in which each face of the resistance sheet is in the form of a double wall, the inner member of which is provided with openings.

In testimony whereof I have hereunto set my hand this 5th day of December, A. D. 1927.

EMIL FRIEDRICH RUSS.
